CLAIM

The ornamental design for a connector component for a lanyard assembly for wire-pulling purposes, as shown and described.

DESCRIPTION

FIG. 1 is a front view of the first embodiment of our connector component for a lanyard assembly for wire-pulling purposes showing our new design;

FIG. 2 is a left side view thereof, the right side view thereof being a mirror image;

FIG. 3 is a rear view thereof;

FIG. 4 is a top view thereof, the bottom view thereof being a mirror image;

FIG. 5 is a longitudinal cross-sectional view taken along line 5-5 of FIG. 4;

FIG. 6 is a front view of a second embodiment of our connector component for a lanyard assembly for wire-pulling purposes showing our new design;

FIG. 7 is a left side view thereof, the right side view thereof being a mirror image;

FIG. 8 is a rear view thereof;

FIG. 9 is a top view thereof, the bottom view thereof being a mirror image;

FIG. 10 is a longitudinal cross-sectional view taken along line 10-10 of FIG. 9;

FIG. 11 is a front view of a third embodiment of our connector component for a lanyard assembly for wire-pulling purposes showing our new design;

FIG. 12 is a left side view thereof, the right side view thereof being a mirror image;

FIG. 13 is a rear view thereof;

FIG. 14 is a top view thereof, the bottom view thereof being a mirror image;

FIG. 15 is a longitudinal cross-sectional view taken along line 15-15 of FIG. 14;

FIG. 16 is a front view of a fourth embodiment of our connector component for a lanyard assembly for wire-pulling purposes showing our new design;

(Continued)

FIG. 17 is a left side view thereof, the right side view thereof being a mirror image;
 FIG. 18 is a rear view thereof;
 FIG. 19 is a top view thereof, the bottom view thereof being a mirror image;
 FIG. 20 is a longitudinal cross-sectional view taken along line 20-20 of FIG. 19;
 FIG. 21 is a front view of a fifth embodiment of our connector component for a lanyard assembly for wire-pulling purposes showing our new design;
 FIG. 22 is a left side view thereof, the right side view thereof being a mirror image;
 FIG. 23 is a rear view thereof;
 FIG. 24 is a top view thereof, the bottom view thereof being a mirror image;
 FIG. 25 is a longitudinal cross-sectional view taken along line 25-25 of FIG. 24;
 FIG. 26 is a front view of a sixth embodiment of our connector component for a lanyard assembly for wire-pulling purposes showing our new design;
 FIG. 27 is a left side view thereof, the right side view thereof being a mirror image;
 FIG. 28 is a rear view thereof;
 FIG. 29 is a top view thereof, the bottom view thereof being a mirror image; and,
 FIG. 30 is a longitudinal cross-sectional view taken along line 30-30 of FIG. 29.
